ALBERT MARKS, OF NEW BRITAIN, CONNECTICUT.

NUMBERING-STAMP AND THE LIKE.

1,335,746.

Specification of Letters Patent.

Patented Apr. 6, 1920.

Application filed June 12, 1918. Serial No. 239,645.

To all whom it may concern:

Be it known that I, ALBERT MARKS, a citizen of the United States of America, residing at New Britain, Connecticut, have invented a new and useful Numbering-Stamp and the like, of which the following is a specification.

My invention relates to printing stamps particularly designed to print numbers. 10 The object of my invention is to improve the mechanical construction by which the printing device or wheels are controlled, whereby these devices may be either automatically or manually controlled at will. In numbering 15 machines of the type particularly referred to herein there is a style termed a "lever" machine in which the printing wheels are controlled by a manually operable lever. There is also a style termed the "automatic" in 20 which the said wheels are automatically operated.

The object of my invention is to combine in one instrumentality all of the advantages of both the "lever" and the "automatic" 25 types, and to do this in a comparatively simple manner by the use of simple parts so constructed and arranged to be effective and durable. In many respects it will be seen that my present invention is an improvement 30 on the construction set forth in my former Patent No. 1,155,595 of October 5, 1915, to which reference will be made for a detail description of such parts as are in common to that machine and to the present machine.

35 In the accompanying drawings:

Figure 1 is a front elevation of my machine with the parts set for printing in duplicate consecutive numbers.

Fig. 2 is a section on the line 2—2 of 40 Fig. 1.

Fig. 3 is a side elevation of the upper part of the frame of the machine shown in Fig. 1 illustrating the setting device.

Fig. 4 is a section on the line 4—4 of 45 Fig. 1.

Fig. 5 is a perspective view of certain details.

Fig. 6 is a sectional view similar to Fig. 4 but showing certain parts in a different position.

Fig. 7 is a perspective view of a detail of construction.

Fig. 8 is an end elevation of another detail.

1 represents the main frame which includes a top, two side pieces and a bottom plate 2, which latter has a central passage for the printing type. 3 is a type wheel carrier frame mounted to move up and down in the main frame 1. 4—4 are type or numbering wheels mounted on a shaft 5 non-rotatably mounted in the frame 3. Each numbering wheel is provided with a spring pressed detent 6 which detents are carried by the shaft 5, said detents functioning to hold the numbering wheels in the proper printing position. 7—7 are nine shallow notches in the external periphery of each wheel at one side of the figures or type thereon. These notches are designed to receive the teeth of a comb 60 hereinafter described, which may oscillate to force the type wheels ahead for consecutive numbering. In each wheel there is also a deep notch 8 arranged between the ends of the series of shallow notches 7—7 for the purpose hereinafter described. 9 is a plunger moving up and down through the top of frame 1, said plunger being connected to the wheel carrier frame 3 and being provided with a handle 10 at its upper end. 11 is a sleeve on frame 1 surrounding the plunger 9 and projecting into the bore of the handle 10. 12 is a spring between sleeve 11 and plunger 9 to normally force the latter upwardly to retract the frame 3. 13 is an ink 70 pad carrier frame. This frame is pivotally mounted at 14—14 on the opposite side walls of the wheel carrier frame 3 near the top. The lower end of the frame 13 stands near the rear edge of the bottom plate 2 and is 75 beveled or inclined as best seen in Figs. 2, 4 and 6, hence, when the wheel carrier frame 3 is forced down, the pad carrier frame will be forced to swing back or to the right as viewed in the aforesaid figures, whereby the 80 pad will move away from the type wheels as the latter descend. 15 is an inking pad mounted in a suitable tray 16 pivoted at 17 in the opposite sides of the frame 13 near the bottom, see Fig. 2. 18 is an upwardly extending arm or plate at the back of the tray 16 which is preferably slightly yielding and which when the parts are in the position shown in Fig. 2 strikes against the rear side 85 of the type wheels so as to swing the pad 15 up against the lower type as shown to ink the same. 19 is a spring lip projecting downwardly from tray 16 which acts as a stop to 90

prevent the tray 16 from dropping too far when the frame 13 swings back.

20 is what I will term a comb carrying frame which is pivoted on screws 21-21 at the ends of bracket 21^a (see Fig. 7), said screws being substantially concentric with shaft 5 whereby said frame may be swung concentrically with the type wheel. The bracket 21^a may be secured to the face of 10 the type wheel carrier 3 by screws 21^b-21^b. The frame 20 constitutes a lever, and 22 is a handle thereon by which the same may be conveniently moved up and down by hand for the purpose of advancing the type wheels 15 manually.

23 is a comb provided with a series of teeth 24-24 of progressively increasing length and corresponding in number to the type wheels, the longest of the teeth being 20 adjacent to the unit wheel which, as shown, is the wheel located at the right hand side of the series shown in Fig. 1. This comb 23 is pivotally mounted at 25 near the outer end of the lever frame 20, and 26 is a spring 25 which normally causes the comb to swing on its pivot so that the ends of the comb will press toward the type wheels. The lever frame 20 may partake of a sufficient range of oscillating movement to permit the 30 comb to engage and advance the type wheel or wheels one number with each oscillation.

In Figs. 1, 2 and 4, I have shown the frame in its lowered position for automatic action, with the longest tooth in engagement 35 in one of the shallow notches of the unit wheel. I have also shown the frame as locked in this position, see Fig. 3, whereby when the plunger 9 is forced down, it will cause the mechanism to automatically advance 40 said unit wheel. This is effected in the following way: 27 is the stationary shoulder carried on the inner side of the frame plate at the right hand side of the main frame 1, as viewed in Fig. 1. 28 is a 45 cam shoulder depending from the side of the comb carrying frame or lever 20, the incline thereof being located directly over the shoulder 27 so that when the type wheel carrier descends carrying down the inner end of the 50 comb carrying frame 20, the cam shoulder 28 will engage the fixed shoulder 27 and cause an upward movement of the comb relatively to the type wheels so that the comb teeth will move back the distance of one 55 notch to engage the next notch to the rear. When this occurs the ascending movement of the wheel carrying frame will carry up the inner end of the comb carrying frame 20 and the latter will strike against a stop shoulder 29 on the inside of the main frame 1, whereby the comb carrying frame 20 will 60 partake of a rocking movement relatively to the type wheels, so that the comb will tend to push ahead or advance one or more of 65 the type wheels according to the number of

comb teeth in engagement therewith. The function of the deep notch in each of the type wheels is to permit the respective comb tooth therefor to drop therethrough once in every complete revolution of the type wheel 70 to such a degree that the next comb tooth can engage a shallow notch in the next type wheel to advance the latter one number.

The construction and operation of the inking mechanism and the type wheel mechanism thus far disclosed, is very much like that shown in my former patent, to which reference may be had for a further detailed description as to automatic function.

Suffice it to say in the present case, that 80 when the parts are set as shown in the drawings, and ignoring parts not already described, the device will automatically operate to print numbers in relative succession on each reciprocation of the plunger 9.

The stop shoulder 29 is pivotally mounted at 30 on the main frame 1, and said shoulder 29 is provided with a lateral offset 31 projecting out through an arcuate slot in the side wall of the main frame 1. On the outside of the frame is a finger plate 32 mounted to swing on a pivot screw 33, said screw passing through a slot 34 in plate 32 whereby the plate may be slid up and down. In the lower side of the arcuate slot, I provide 95 two notches 35-36. 37 is a nose on the plate 32 which extends into the arc-shaped slot and which may be shifted into either of the notches 35-36 by sliding the plate on the stud 33. When the nose 37 stands in 100 either one of these notches it is obvious that the plate cannot move, and since this plate has a slot into which the lateral offset 31 of the stop shoulder 29 projects, it is obvious 105 that the stop shoulder 29 will be locked in that position. In Fig. 3 I have shown the stop shoulder 29 as locked in the position for automatic consecutive numbering and for automatic duplication of numbers as later 110 described. In Fig. 6, I have shown the stop shoulder 29 as shifted and locked in an out of the way position so that the automatic advance of the wheels will not occur since in that position the stop shoulder 29 permits the comb carrying frame or lever 20 to 115 ascend to such a degree that the reciprocation up and down of the plunger 9 will not have the effect of causing the comb teeth to engage and advance the type wheels. However, it will be observed that at such a time 120 the operator by engaging the handle 22 with the fingers may oscillate the lever and advance the comb teeth manually, whereby the mechanism may be operated after the style of a so-called "lever" machine.

When it is desired to set the machine for the automatic duplication of numbers, I again move the stop shoulder 29 down into the position shown in Fig. 4, and I also provide means to hold the comb out of the 130

type wheel engaging position on each alternate upward reciprocation of the plunger 9. This means is best illustrated in the perspective view, Fig. 5, and will be seen to comprise the following instrumentalities. 5 (Figs. 5 and 8) is what I may term a cam wheel mounted on the shaft 5 and held by a spring pawl 39 which engages internal ratchet teeth on the wheel 38 to prevent 10 said wheel from turning backward. This wheel as shown in Fig. 8, is provided with four equally spaced external ratchet teeth 40—40, and with four equally spaced deep notches 41 arranged half way between the 15 ratchet teeth 40—40. 42 is a pawl on the end of the comb arranged to ride on the edge of the wheel 38. In Fig. 5 the point of the pawl 42 is shown as dropped into one of the deep notches of the wheel 38 and 20 against the shoulder at the end thereof. This permits the comb to drop into the type wheel engaging position whereby on the next ascending movement of the plunger 9, such wheel or wheels as are engaged by 25 comb teeth will be advanced one tooth. On the downward reciprocation of the plunger, the comb will be drawn back into position to engage the next notch or notches to the rear on the type wheel or wheels, but such 30 engagement will not be permitted on the next ascending movement of the plunger, because at such a time the point of the pawl 42 will rest on the top of the wheel 38 behind one of the ratchet teeth 40, hence, 35 when the plunger next descends, although the comb will be moved, the number previously printed will be repeated. Simultaneously, the wheel 38 will be advanced one tooth so that the point of the pawl 42 40 may drop into the next deep notch to the rear, which as before described, will permit the comb to again perform the wheel advancing function on the next upward movement of the plunger 9. 45 The pawl 42 is adjustable. That is to say, when it is desired to duplicate each number, it will be positioned as shown in Fig. 5, but when it is desired to set the machine for automatic consecutive numbering, the pawl 42 is shifted so that its point will not engage the cam wheel 38 as previously described. This may be accomplished in a variety of ways, but in the preferred form shown in the drawing, I mount 50 the pawl 42 so that it may be slid longitudinally on the end of the shaft 44 which constitutes the pivot mounting for the comb. On the end of the comb 23 I provide a pin 45, the end of which may be seen in Fig. 5 as standing in a hole 46 in the pawl 42 to lock the pawl 42 to the comb. Near the point of the pawl 42 I provide another hole 46^a of suitable size to slide over the pin 45. By lifting the comb so as to withdraw the 55 point of the pawl 42 from engagement with the wheel 38, the said pawl may be slid to the left on the shaft 44 to disengage it from the pin 45 whereupon the pawl may be swung up so that the pin will enter the hole 46^a to lock the pawl to the comb in this second position. A spring 47 may be provided to retain the pawl in the position in which the pin projects into one or the other of the aforesaid holes. Obviously, when the parts are in this position, the pawl 42 and the 60 wheel 38 will be functionless and hence the type wheels will be automatically advanced one movement on each upward movement of the plunger 9. 43 is a stop shoulder on the forward side of the pawl 42, the function of which is to prevent the machine from jamming when the maximum movement is reached and the wheels are about to turn back to zero, for at such a time it is obvious that unless effective means were 65 provided to prevent the excessive downward movement of the comb since at that time all the deep notches in the numbering wheels are in alinement with the comb teeth, the comb would drop to such a degree as to 70 cause the mechanism to jam. To that end I provide the stop shoulder 43 which will check the inward movement of the comb at the limit of its safe movement whereby when the numbering wheels turn back to 75 zero that turning movement will be executed with certainty and without the aforesaid danger to jamming since the stop shoulder 43 will be supported by the cam wheel 38, and the comb will be prevented from unduly 80 dropping.

From the foregoing it is apparent that the apparatus described combines in one machine all of the advantages heretofore obtained by different types or styles of machines, which is obviously of great advantage. While I have shown my invention in a preferred form, it is obvious that the various details may be modified in design and arrangement in many ways without departing from the spirit or scope of my invention. 85

What I claim is:

1. In a numbering stamp and the like, a main frame, a series of rotatable type wheels, a carrier therefor mounted to move up and down in said main frame, a movable lever frame carrying a comb, means co-acting with said lever frame for causing the same to operate automatically on the reciprocation of the type wheel carrier under certain conditions 115 and for permitting said comb to be manually operated under other conditions, the means for effecting automatic action comprising a cam on said lever frame and a relatively stationary shoulder on the main 120 frame for co-action with said cam, and a stop shoulder on said main frame for co-action with another part of said lever frame when said stop shoulder is in one position, said stop shoulder being movable into a 125 130

second position wherein it ceases to co-act with said lever frame whereby the latter will cease to operate automatically.

2. In a numbering stamp and the like, a main frame, a series of rotatable type wheels, a carrier therefor mounted to move up and down in said main frame, a movable comb for advancing said wheels step by step, a lever frame carrying said comb, means co-acting with said lever frame for causing the same to operate automatically on the reciprocation of the type wheel carrier under certain conditions and for permitting said comb to be manually operated under other conditions, and means for holding said comb out of the type wheel engaging position for certain periods during automatic action to permit duplicate printing, said means coacting with the lever frame comprising a relatively stationary shoulder on the main frame and a stop shoulder on the main frame for engagement with another part of said lever frame.
3. In a numbering stamp and the like, a main frame, a series of rotatable type wheels, a carrier therefor mounted to move up and down in said main frame, a movable lever frame carrying a comb, means co-acting with said lever frame for causing the same to operate automatically on the reciprocation of the type wheel carrier under certain conditions and for permitting said comb to be manually operated under other conditions, the means for effecting automatic action comprising a cam on said lever frame and a relative stationary shoulder on the main frame for co-action with said cam, and a stop shoulder on said main frame for co-action with another part of said lever frame when said stop shoulder is in one position, said stop shoulder being movable into a second position wherein it ceases to co-act with said lever frame whereby the latter will cease to operate automatically, and means for locking said stop shoulder in either one of the aforesaid positions comprising a latch movable in a slot in the main frame and engageable with the wall of said slot at different positions.
4. In a numbering stamp and the like, a main frame, a series of rotatable type wheels, a carrier therefor mounted to move up and down in said main frame, a movable lever frame carrying a comb, means co-acting with said lever frame for causing the same to operate automatically on the reciprocation of the type wheel carrier under certain conditions and for permitting said comb to be manually operated under other conditions, the means for effecting automatic action comprising a cam on said lever frame and a relatively stationary shoulder on the main frame for co-action with said cam, and a stop shoulder on said main frame for co-action with another part of said lever

frame when said stop shoulder is in one position, said stop shoulder being movable into a second position wherein it ceases to co-act with said lever frame whereby the latter will cease to operate automatically, and means for locking said stop shoulder in either one of the aforesaid positions, comprising a movable plate on the outside of the frame.

5. In a numbering stamp and the like, a main frame, a series of rotatable type wheels, a carrier therefor mounted to move up and down in said main frame, a movable comb for advancing said wheels step by step, a lever frame carrying said comb, means co-acting with said lever frame for causing the same to operate automatically on the reciprocation of the type wheel carrier under certain conditions and for permitting said comb to be manually operated under other conditions, and an inking device pivotally mounted and spring supported on said type wheel carrier and movable to an out-of-the-way position when said carrier is advancing in a direction to print.

6. In a numbering stamp and the like, a main frame, a series of rotatable type wheels, a carrier therefor mounted to move up and down in said main frame, a movable comb for advancing said wheels step by step, a lever frame carrying said comb, means co-acting with said lever frame for causing the same to operate automatically on the reciprocation of the type wheel carrier under certain conditions and for permitting said comb to be manually operated under other conditions, a bracket on the type wheel carrier, said lever frame being pivoted on said bracket concentrically with said type wheels.

7. In a numbering stamp and the like, a main frame, a plurality of rotatable type wheels, a carrier therefor mounted to move to and fro on said main frame, said type wheels each bearing the numerals 0, 1, 2, 3, 4, 5, 6, 7, 8 and 9, a shallow notch in the side of each wheel adjacent to all of the numerals excepting the numeral 9, a deep notch adjacent to this numeral on each of said wheels, a comb having teeth of a number corresponding to the type wheels employed, said teeth being of progressively increased length, the longest tooth being adjacent to the type wheel designed to print the lowest number, a member having a tooth and a shoulder adjacent said tooth to engage a member on the type wheel shaft for operating said comb upon the reciprocation of the type wheel carrier, and means to prevent said comb from dropping beyond a predetermined limit to prevent jamming when all of the deep notches in the aforesaid type wheels are in alinement.

8. In a numbering stamp and the like, a main frame, a series of rotatable type wheels, a carrier therefor mounted to move up and

down in said main frame, a movable comb for advancing said wheels step by step, a lever frame carrying said comb, means co-acting with said lever frame for causing the same 5 to operate automatically on the reciprocation of the type wheel carrier under certain conditions and for permitting said comb to be manually operated under other conditions, and means for holding said comb out 10 of the type wheel engaging position for certain periods during automatic action to permit duplicate printing, said means having a shoulder to limit the movement of the comb in one direction to prevent jamming 15 the machine.

9. In a numbering stamp and the like, a main frame, a type wheel carrier mounted to reciprocate between the sides thereof, a non-rotatable shaft carried by the sides of 20 the type wheel carrier, a series of rotatable type wheels mounted on said shaft and arranged to be advanced thereon step by step, means for moving said type wheel carrier up and down, an inking device pivoted on 25 said type wheel carrier and normally in engagement with certain type on said type wheels, with means for moving said inking device into an out of the way position when said type wheels are moved in a direction 30 to print, means for advancing said wheels comprising a lever frame, a bracket carried by said type wheel carrier, the ends of said bracket overstanding the ends of the aforesaid shaft, said lever frame being 35 pivotally mounted on said bracket concentric with said shaft, a comb pivotally mounted near the outer end of said frame, a stop on the main frame for engaging the lever frame between its ends to cause the 40 same to rock in one direction when the type

wheel carrier is moved in one direction and another stop on the main frame arranged to engage the lever frame between its ends to cause the latter to rock in an opposite direction upon the opposite movement of 45 said type wheel carrier, the last mentioned stop holding said frame against rising beyond a predetermined distance for automatic action, said last mentioned stop being movable to an out of the way position to permit 50 said frame to rise and normally stand above said predetermined position whereby at such time the type wheel can be advanced only by manual operation of said lever frame.

10. In a numbering stamp and the like, a main frame, a rotatable type wheel, a carrier therefor mounted to move in said frame, a comb co-operating with said type wheel, a member carrying said comb, means for advancing said type wheel automatically upon movement of the carrier, the means for effecting automatic movement comprising a cam on said comb carrying member and a relatively stationary shoulder on the main frame for coaction with said cam, and a stop 60 shoulder on said main frame for coaction with another part of said comb carrying member when said stop shoulder is in one position.

11. The combination set forth in claim 10, 70 said stop shoulder being movable into a second position wherein it ceases to coact with said comb carrying member.

12. The combination set forth in claim 10, 75 said stop shoulder being movable about a pivot on the main frame and means for locking said stop shoulder in various positions comprising a notched plate on the main frame.

ALBERT MARKS.
